COMBINED CABINET AND DRAWER WITH
COMPRESSING AND SIGNALING MEANSMilton Effros, New York, and Charles E. Mills,
Floral Park, N. Y.

Application November 16, 1943, Serial No. 510,485

24 Claims. (Cl. 45—2)

1

This invention relates to filing cabinets.

The invention, although applicable in many other relations, will be described herein specifically in relation to its use in file cabinets having drawers for storing the cards used in tabulating machines. These cards generally are of very thin stock; large numbers of them are fed automatically into the tabulating machine, and there produce the desired accounting, printing or similar result. In order that the card fed to the machine may cooperate properly with the machine in producing the desired result, the card may not be distorted. In fact, the card must, at the time of its movement into cooperation with the machine, maintain substantially a flat condition, as any marked bowing of the card may hinder proper operation of the tabulating machine. For instance, the bowed card may jam the apparatus.

The cards, when not in use, are stored in the drawer, and are disposed substantially vertically, that is, on edge, to facilitate individual inspection and handling. In order to prevent bowing of the cards, the cards, when they are not being inspected or otherwise handled individually, are maintained in their drawers under sufficient pressure to cause the cards to retain their substantially flat state. A slidable wall, or follower block, is associated with the drawer for that purpose. This follower block is pushed up against the cards arranged in the drawer until engagement takes place; then the block is forced further until no further movement can occur. Mechanism is provided as a part of the drawer structure to lock the block in this last position.

However, operatives, whose duty it is to supervise the cards in the drawers, and assure that the cards are under proper compression, may overlook this necessity, fail to push the block into the required position, and leave the cards to become distorted. The resultant sagging, and, finally, bowing, of the cards, may become permanent, so that the cards would be useless for properly operating a tabulating machine.

It is an object of the invention to provide mechanism for disposing a warning, to be seen by operatives, regarding the condition of the cards in a file cabinet drawer, so that an operative may then insure that the follower block be moved into proper pressure-applying position.

It is an object of the invention to provide mechanism, in conjunction with a card storage drawer, to insure against closing the drawer unless the follower block had been adjusted properly for maintaining the cards in the drawer under compression.

2

It is an object of the invention to provide apparatus, in association with a cabinet, a card storage drawer of the cabinet, and a follower block therewith associated, for assuring that the follower block will be moved automatically into card-compressing position when it is attempted to move the drawer into housed relationship in the cabinet if the follower block has not already been manipulated to card compressing position.

It is an object of the invention to provide, in association with apparatus operating automatically to prevent closing of the drawer unless material stored therein, such as cards, has been placed under compression, mechanism for making such apparatus inoperative in the event that the drawer is moved to drawer-closing position when the drawer contains substantially no material to be placed under compression.

It is an object of the invention to provide mechanism, in association with a drawer, the cabinet with which such drawer is associated, and apparatus for preventing closing of the drawer until the material contained in the drawer has been placed under proper compression, to assure that the drawer may be opened without interference from such apparatus in the event such apparatus should accidentally become released.

Other objects of this invention will be set forth hereinafter, or will be apparent from the description and the drawings, in which is illustrated an embodiment of apparatus for carrying out the invention.

The invention, however, is not intended to be restricted to any particular construction, or to any particular arrangement of parts, or to any particular application of any such construction or any such arrangement of parts, or to any specific method of operation, or to any of the various details thereof, even where specifically shown and described herein, as the same may be modified in various particulars, or may be applied in many varied relations, without departing from the spirit and scope of the claimed invention, a practical construction embodying certain details of the invention being illustrated and described, but only for the purpose of complying with the requirements of the statutes for disclosure of operative embodiments, and without attempting to disclose all of the various forms and modifications in which the invention might be embodied.

On the drawings, in which the same reference characters refer to the same parts throughout, and in which is disclosed such practical construction:

Fig. 1 is a view of a card drawer having a fol-

lower block mounted therein, and embodying the invention, the view being in transverse vertical cross-section, and looking rearwardly into the drawer, parts of the block guiding and retaining apparatus and the cabinet for the drawer not being shown;

Fig. 2 is a view similar to Fig. 1, taken in the opposite direction, and parts of the block guiding and retaining apparatus being shown, parts thereof being broken away, and the cabinet for the drawer not being shown; and

Fig. 3 is a view, in vertical cross-section, substantially on the line 3—3 of Fig. 1, showing the drawer extended into the drawer opening of a cabinet, only portion of the cabinet and of the cards to be contained therein being shown, the drawer being broken away, and different positions of the signalling means being illustrated in dotted and dot-and-dash lines.

Fig. 4 is a fragmentary view taken on line 4—4 of Fig. 2.

Fig. 5 is a fragmentary view taken on line 5—5 of Fig. 2.

On the drawings, a portion of a storage cabinet 10 is shown. Just a portion of the front wall 12 is illustrated; an opening 14 through wall 12 provides access for sliding a card drawer 16 into and out of housed relation to cabinet 10. The particular details of construction of card drawer 16, or of the suspension of the drawer for sliding movement through opening 14, are not believed necessary for illustration.

The drawer may include side walls 18, a bottom 20 and a front wall 22. Front wall 22 may be of reinforced construction, and may have extending sections 24 and 26, which, together with wall 22, completely close the opening 14 formed in wall 12 between cross-pieces 28, when the drawer is moved into the cabinet to housed position. Drawer 16 may be mounted in a cradle (not shown) of any desired construction in order that it may be extended from the cabinet to as great a degree as possible, for making substantially the entire storage space 30 of the drawer accessible. Angle irons 32 may be mounted on side walls 18 for cooperation with such supporting elements.

In the drawer is mounted means for placing material stored therein under compression. Such means may take the form of a follower block 34 slidable through space 30. Such block may be of any desired construction. For instance, it may be formed of sheet metal to provide a plate 36, terminating in a channel formation 38 at the top of the plate. The edges 40 may be spaced from walls 18 and bottom 20.

In order to guide block 34 in its movement through space 30, walls 18 may be bent or otherwise formed to provide channels 42. An angle 44 may be secured to a wall 46 of the recess 48 in each of channels 42 to provide grooves 50. The bases 52 of a pair of L-shaped members 54 are affixed adjacent the top of plate 36 so that arms 58 of members 54 extend forwardly from block 34. Arms 58 take the form of angles each of which has an horizontal leg 60. This leg is received in groove 50 and is guided thereby as the legs, with plate 36, are slid along the drawer. The nesting of legs 60 in grooves 50 serves to rigidify block 34 and holds it against cocking as it slides along the drawer.

The block may be provided with suitable mechanism to retain it in a position to which it may have been adjusted, and thus prevent the block from moving backwards along the drawer under the pressure of the compressed cards. Such

mechanism provides for its release when cards are to be inserted or withdrawn from the cabinet. Any desired well-known mechanism for that purpose is suitable for the purposes herein described.

The apparatus specifically shown is merely for the purpose of illustration. A pair of arms 62 are mounted pivotally, as at 61, upon base 52 of member 54; their ends 63 extend into recesses 48. On the face of each arm 58 towards its recess 48 a finger 64 formed with a point 66 is pivoted at 71. Finger 64 has an end 67 formed with an opening 69 into which end 63 of arm 62 seats. Thus movement of arms 62 about their pivots will cause movement of fingers 64 about pivots 71. Springs 68, anchored between arms 62 and plate 36, serve to move arms 62 and the associated fingers 64 automatically to jam points 66 against faces 70 of angles 44, this being the normal position. Thus, such engagement prevents movement of block 34 rearwardly of space 30. However, points 66 have such direction, as appears in Fig. 3, that, on movement of block 34 forwardly of the drawer, release of such engagement ensues, and the block is free to move, the points sliding over faces 70. Block 34 may not be moved away from wall 22 unless points 66 are disengaged from faces 70. The conventional finger 76 actuates a slide 77. The slide has flanges 79 which are retained for sliding movement with relation to plate 36 by means of ears 81 struck from or otherwise provided on the plate. Arms 62 have their ends caught in cut-outs 3 in slide 77 and are moved, by movement of slide 77, to rock fingers 64 for disengaging points 66 from faces 70. Springs 68 return the parts so that points 66 re-engage faces 70.

Carried upon plate 36 at its rear face 78 are a pair of brackets 80. Each bracket has an end bent and slotted to provide a pair of ears 82. A pivot pin 84 is provided a loose bearing in each pair of ears. A finger 86, mounted on and fixed relatively to pivot pin 84 by means of a set-screw 88, is positioned between a pair of ears 82. Finger 86 extends forwardly from its bracket 80 through a slot 90 in plate 36 to provide an engaging section 92 extending beyond front face 94 of plate 36.

Finger 86 includes a rearwardly extending arm 96 which is received within a fork 98 formed in the lower end of a rod 100. Arm 96 and forked end 98 are loosely pinned together to provide a pivotal connection 102. Rod 100 is mounted for sliding movement through a bracket 104, secured to a flange 106 of channel formation 38. A spring 108 may be engaged on bracket 104 and on pivot pin 102, and tends normally to move rod 100 vertically, and to move finger 86 to a position in front of face 94 of plate 36. Rod 100 is of such length that, when spring 108 is effective as just indicated, the rod will extend beyond the upper level of front wall 22 and its section 24.

As shown on the drawings, each block 34 may have a plurality of rods 100; a pair of rods 100 are shown mounted, with substantially identical associated parts on a single block 34. When cards are not located in space 30, or when block 34 has not been moved into position to compress cards in the drawer, spring 108 moves rod 100 up above the top edge of wall 22; finger 86 is then positioned in front of plate 36. Drawer 16 cannot be moved into cabinet 10 since rod 100 will engage front wall 12 at cross-piece 28, as can be seen from Fig. 3. However, when cards or like material engage against face 94, and, therefore, are effective to move finger 86 through slot 90 by pressing against section 92 and overcoming the

effect of spring 108, rod 100 will be moved down to the position shown in dot-and-dash lines in Fig. 3, and will not be above the top level of front wall 22 and its section 24. Thus, in the first position, rod 100 will be in position to engage cross-piece 28. In the retracted position, the drawer may be moved in and out of the cabinet without interference from rods 100.

Of course, if the operative should attempt to push the drawer into the cabinet against the resistance of rods 100, the engagement of rods 100 with cross-piece 28 will cause block 34 to move through the drawer, points 66 sliding over faces 70, until front edges 110 of arms 58 engage against stop sections 112 at the ends of recesses 48. By reason of the length of arms 58, the drawer still will not close if no cards are in the drawer, since nothing has engaged finger 86, thus spaced from wall 22, to move rod 100 downwardly to clear the bottom edge 114 of cross-piece 28.

If cards 116 are located in space 30, finger 86 is engaged against these cards as plate 36 is moved into engagement with such cards. The tension of spring 108 is sufficient to keep finger 86 extended until the cards have been pushed by block 34 into abutment with face 118 of front wall 22. Then, continued movement of block 34 will cause compression of the cards, and, therefore, pivoting of finger 86 against the action of spring 108 to move rods 100 downwardly until the top edges 120 of the rods have cleared edge 114. Then, and not until then, is it possible to push the drawer completely into the cabinet; at such time, of course, the cards have already been placed under the desired compression. Prior to movement of the drawer to compress the cards in this manner, extension of rods 100 above the top level of the drawer will signal that the follower block had not been manipulated properly. As a matter of fact, the crack of the rod against the front wall of the cabinet is sufficient to warn that the undesired condition existed. Of course, it is possible manually to move block 34 to compressing position when the signalled condition is observed.

In those cases, however, where sufficient cards are not present in the storage space, that is, the drawer is substantially empty, and still it is desired to close the drawer, mechanism must be provided for releasing rods 100 from interfering with such closing movement. For this purpose, pin 84 is extended into an arm 122. Arm 122 extends beyond plate 36 towards channel 42, and particularly a face 124 of the channel. On face 124, a raised portion 126 may be formed; in this case, a small plate is applied on face 124 and forms a projection into space 30. Portion 126 is positioned so that, just before arms 58 engage stop section 112, the end portion of arm 122 will be engaged by portion 126, and arm 122 will be rocked to pivot finger 86 and move rods 100 downwardly into the drawer out of closing-preventing position.

It may occur that the mechanism, including member 54, points 66 and faces 70, may be released accidentally when the drawer is in completely housed position. In such case, rods 100 would become extended upwardly by springs 108, and the rods would then prevent movement of the drawer to open position as the rods would engage the inner faces of cross-piece 28, or similar parts of the inner structure of the cabinet. In order to avoid this undesired condition, rod 100, at its upper end, is formed with a cam face 128 inclined in a direction such that, as the

drawer is moved to open position, such cam face will engage within the cabinet against the edge of the obstructing part, as shown in dotted lines in Fig. 3. As face 128 engages against this cross-piece, it will tend to push rod 100 downwardly against the action of spring 108, so that the rod can then slide along the bottom face of the obstructing portion until the rod or rods are free of the cabinet, at which position the rods can then be manipulated manually.

In order better to warn an operative as to the condition of the cards within a drawer, a visual signal may be associated with front wall 22. In this case, an opening 130 may be provided in the front section 132 of front wall 22. A pivoted bell crank 134 may be mounted on a bracket 136 on the inner section 138 of wall 22. One arm of crank 134 may carry a signal flap 140, which, under suitable conditions, would be seen through opening 130. The other arm 142 of the crank may extend through a slot 144 in section 138 to provide a finger for engagement by cards within the drawer. A coiled spring 146 on pivot 148 functions between crank 134 and section 138 so that flap 140 would normally be positioned at opening 130. When cards, however, would be compressed against section 138 by follower block 34, the cards will engage arm 142 and move the crank against spring 146 to cause flap 140 to move away from and not be clearly apparent as a signal at opening 130. Then, for instance, if flap 140 be colored red, this red signal would only appear in the event either no cards are in the cabinet or the cards have not been compressed against section 138. Thus, a supervisor would be able immediately to determine what drawers are being used properly, without opening the drawers themselves, and also to determine whether the follower blocks in full drawers had become released accidentally.

Many other changes could be effected in the particular apparatus designed, and in the method of operation set forth, and in specific details thereof, without substantially departing from 45 the invention defined in the claims, the specific description being merely of an operative embodiment capable of illustrating certain principles of the invention.

What is claimed as new and useful is:

1. A follower block for a card-retaining drawer of a cabinet, wherein the drawer is capable of retaining a plurality of substantially identical cards in substantially vertical position, and wherein the follower block is movable into position to compress the cards in the drawer to cause all of them simultaneously to assume the substantially vertical position, the follower block having a wall for engagement against the cards for forcing them into position, means carried by the block to be engaged by the cards in the drawer for signalling the operative relation of the block to the cards, the signalling means including a movable finger carried by the wall and extending towards cards to be compressed, means normally projecting beyond the bounds of the drawer, and means controlled by the finger for withdrawing the projecting means from beyond the normal bounds of the drawer to a position substantially entirely within the bounds of the drawer when the follower block engages against the cards in the drawer and compresses them.

2. A follower block for a card-retaining drawer of a cabinet, wherein the drawer is capable of retaining a plurality of substantially identical cards in substantially vertical position, and

wherein the follower block is movable into position to compress the cards in the drawer to cause all of them simultaneously to assume the substantially vertical position, the follower block having a wall for engagement against the cards for forcing them into position, means carried by the block to be engaged by the cards in the drawer for signalling the operative relation of the block to the cards, the signalling means including a movable finger carried by the wall and extending towards cards to be compressed, and means mounted for movement between a position below the top level of the block and to project above the top level of the block, the finger providing means for retracting the projection means from a position above the top level of the block.

3. The combination with a cabinet, and a drawer mounted for movement into and out of the cabinet through an opening in a wall of the cabinet, the drawer providing means for retaining a plurality of cards in stacked relationship, of means in the drawer for compressing the stacked cards, a signal, and means tending normally to move the signal beyond the extent of the drawer into position to indicate the compressing means to be in ineffective relation to the cards, and means for operation by the compressed cards when the compressing means has been effective properly to compress the cards to move the signal out of the ineffective-indicating position.

4. The combination with a cabinet, and a drawer mounted for movement into and out of the cabinet through an opening in a wall of the cabinet, the drawer providing means for retaining a plurality of cards in stacked relationship, of a wall adjustable in the drawer for compressing the stacked cards, means for retaining the adjustable wall against movement out of a card-compressing position to which it has been adjusted, a member carried by the adjustable wall, and means for maintaining the member in position to be engaged by a portion of the cabinet to move the adjustable wall to compress cards in the drawer when the drawer is moved into housed relation.

5. The combination with a cabinet, and a drawer mounted for movement into and out of the cabinet through an opening in a wall of the cabinet, the drawer providing means for retaining a plurality of cards in stacked relationship, of a wall adjustable in the drawer for compressing the stacked cards, means for retaining the adjustable wall against movement out of a card-compressing position to which it has been adjusted, a member carried by the adjustable wall, and means to project the member into position to engage the wall of the cabinet when the adjustable wall is not in compressing engagement with cards within the drawer to move the adjustable wall to compress cards in the drawer when the drawer is moved into housed relation.

6. The combination with a cabinet, and a drawer mounted for movement into and out of the cabinet through an opening in a wall of the cabinet, the drawer providing means for retaining a plurality of cards in stacked relationship, of a wall movable in the drawer for compressing the stacked cards, means for interfering with movement of the drawer into housed relationship in the cabinet, and means adapted to be acted upon by the compressed stacked cards in the drawer to disable the interfering means.

7. The combination with a cabinet, and a drawer mounted for movement into and out of the cabinet through an opening in a wall of the

cabinet, the drawer providing means for retaining a plurality of cards in stacked relationship, of a wall movable in the drawer for compressing the stacked cards, a signal carried by the movable wall, means tending normally to move the signal relatively to the movable wall and the cabinet to indicate the position of the movable wall in relation to the cards, and means carried by the movable wall and for engagement by cards being compressed to move the signal out of the normal position.

8. The combination with a cabinet, and a drawer mounted for movement into and out of the cabinet through an opening in a wall of the cabinet, the drawer providing means for retaining a plurality of cards in stacked relationship, of a wall adjustable in the drawer for compressing the stacked cards, means for retaining the adjustable wall against movement out of a position to which it has been adjusted, means for interfering with movement of the drawer into housed relationship in the cabinet, and means adapted to be acted upon by the compressed stacked cards in the drawer to disable the interfering means.

9. The combination with a cabinet, and a drawer mounted for movement into and out of the cabinet through an opening in a wall of the cabinet, the drawer having a front wall and providing means for retaining a plurality of cards in stacked relationship, of a wall adjustable in the drawer for compressing the stacked cards against the front wall, means for retaining the adjustable wall against movement out of a position to which it has been adjusted, means for interfering with movement of the drawer into housed relationship in the cabinet until the adjustable wall has compressed the cards, and means operable by inward movement of the drawer for making the interfering means ineffective when there are substantially no cards in the drawer.

10. In combination, a cabinet, a drawer for retaining material stored in the cabinet, the drawer being mounted in the cabinet for movement to be capable of projection from the cabinet, a block mounted for sliding movement within the drawer, means positionable between the block and the cabinet to cause the block to slide along the drawer when the block is not in compressing engagement with material within the drawer and to engage and compress material within the drawer as the drawer is propelled to move it into the cabinet, and means for retaining the block against movement out of material-engaging-and-compressing position.

11. In a cabinet wherein a drawer is movable into and out of housed relation to the cabinet, and wherein the drawer provides means for retaining material stored in the cabinet, and wherein a block is slidable relatively to the stored material for placing the material under compression; the combination with the block, of means for effecting movement of the block on movement of the drawer into housed relation to compress the stored material, and means automatically to make the movement-effecting means effective when the stored material is not under a predetermined degree of compression and the drawer is being moved into the cabinet.

12. In a cabinet wherein a drawer is movable into and out of housed relation to the cabinet, and wherein the drawer provides means for retaining material stored in the cabinet, and wherein a block is slidable relatively to the stored material for placing the material under compres-

sion; the combination with the block, of means between the cabinet and the block for effecting movement of the block on movement of the drawer into housed relation to compress the stored material, and means automatically to make the movement-effecting means effective when the stored material is not under a predetermined degree of compression and the drawer is being moved into the cabinet.

13. In combination with a cabinet drawer for retaining material stored therein, a follower block in the drawer, the block being associated with the drawer for movement along the drawer into and out of compressive engagement with the stored material, the block having an opening therethrough, a finger pivotally mounted on the block in position to move through the opening, means for causing the finger normally to extend through the opening and project beyond the block towards the stored material, and a rod guided for vertical movement relative to the block, the rod being pivotally connected to the finger and normally projecting above the drawer.

14. In combination with a cabinet drawer for retaining material stored therein, a follower block in the drawer, the block being associated with the drawer for movement along the drawer into and out of compressive engagement with the stored material, the block having an opening therethrough, a pivot pin carried in bearings on the block, a finger fixed to the pivot pin to move through the opening, means for causing the finger normally to extend through the opening and project beyond the block towards the stored material, a rod guided for vertical movement relative to the block, the rod being pivotally connected to the finger and normally projecting above the drawer, and means extending from the pivot pin to engage a part of the drawer to retract the finger through the opening when the drawer is moved into the cabinet and no material is stored in the drawer.

15. In cabinet drawer construction, wherein a drawer is mounted for movement into and out of housed relation to the cabinet through an opening in a wall of the cabinet, the drawer providing means for receiving a plurality of substantially identical cards in stacked relation but with the cards disposed substantially vertically, means carried within the drawer to engage against the stack of cards in the drawer to compress them, and means for engagement by the cards being compressed by the compressing means to move out of a visible signalling position beyond the bounds of the drawer when the compressing means is positively compressing material, the signalling means being constructed normally to extend into the signalling position beyond the normal bounds of the drawer.

16. A follower block for a card-retaining drawer of a cabinet, wherein the drawer is capable of retaining a plurality of substantially identical cards in substantially vertical position, and wherein the follower block is movable into position to compress the cards in the drawer to cause all of them simultaneously to assume the substantially vertical position, a member carried by the block and mounted for movement between limits, one of the limits being substantially entirely within the extent of the drawer, the other limit being beyond the extent of the drawer, and means carried by the block to be engaged by the cards in the drawer for actuating the member to move it from its limit beyond the extent of the

drawer to the limit within the extent of the drawer.

17. The combination with a cabinet, and a drawer mounted for movement into and out of the cabinet through an opening in a wall of the cabinet, the drawer providing means for retaining a plurality of cards in stacked relationship, of means in and movable with relation to the drawer for compressing the stacked cards, and cooperating means between the compressing means and the cabinet to cause an application of force to the cards-compressing means from the cabinet on movement of the drawer into housed relationship in the cabinet when the cards in the drawer are not compressed, the cooperating means providing means to cause relative movement of the compressing means and the drawer to compress the cards to a predetermined degree of compression.

18. The combination with a cabinet, and a drawer mounted for movement into and out of the cabinet through an opening in a wall of the cabinet, the drawer providing means for retaining a plurality of cards in stacked relationship, of a wall adjustable in the drawer for compressing the stacked cards, means for retaining the adjustable wall against movement out of a card-compressing position to which it has been adjusted, a rod mounted upon and movable with relation to the adjustable wall, the rod being movable from a position where it is in line to engage with a portion of the cabinet and interfere with movement of the drawer into the cabinet to a position where it does not project into such interfering position, means for causing the rod normally to move to cabinet-engaging position, and means to withdraw the rod from the cabinet-engaging position when the adjustable wall is in compressing engagement with cards within the drawer.

19. The combination with a cabinet, and a drawer mounted for movement into and out of the cabinet through an opening in a wall of the cabinet, the drawer providing means for retaining a plurality of cards in stacked relationship, of a wall adjustable in the drawer for compressing the stacked cards, means for retaining the adjustable wall against movement out of a card-compressing position to which it has been adjusted, a rod mounted for movement relative to the adjustable wall, a finger movably mounted on the adjustable wall, the finger being positioned relatively to the wall to extend towards cards retained in the drawer and being coupled to the rod, and means for normally projecting the rod into position to engage with a portion of the cabinet as the drawer is moved with relation to the cabinet, the finger comprising means to be engaged by cards within the drawer when the adjustable wall is compressing the cards to move the rod out of cabinet-engaging position.

20. The combination with a cabinet, and a drawer mounted for movement with relation to portions of the cabinet and into and out of housed relation to the cabinet through an opening in a wall of the cabinet, the drawer having a front wall and providing means for retaining a plurality of cards in stacked relationship, of a wall adjustable in the drawer for compressing the stacked cards against the front wall, means for retaining the adjustable wall against movement out of a card-compressing position to which it has been adjusted, a rod mounted for movement relative to the adjustable wall and across the cabinet opening into a position to engage with a cabinet portion on movement of the drawer towards

housed relation, a finger movably mounted on the adjustable wall, the finger being positioned to extend towards cards retained in the drawer and being coupled to the rod, and means to project the rod across the opening for engaging a portion of the cabinet, the finger comprising means to be engaged by the cards being compressed by the adjustable wall to counteract the rod-projecting means and move the rod to a position where it will not engage a cabinet portion on movement of the drawer to housed relation, the adjustable wall and the drawer having cooperating means to make the projecting means ineffective when the adjustable wall is adjusted to a predetermined position with relation to the front wall and the drawer is substantially empty.

21. The combination with a cabinet, and a drawer mounted for movement into and out of the cabinet through an opening in a wall of the cabinet, the drawer having a front wall and providing means for retaining a plurality of cards in stacked relationship, of a wall adjustable in the drawer for compressing the stacked cards against the front wall, means for retaining the adjustable wall against movement out of a card-compressing position to which it has been adjusted, a rod mounted for movement relative to the adjustable wall and across the cabinet opening into a position to engage with a cabinet portion on movement of the drawer towards housed relation, a finger movably mounted on the adjustable wall, the finger being positioned relatively to the wall to extend towards cards retained in the drawer and being coupled to the rod, means to project the rod across the opening for engaging a portion of the cabinet, the finger comprising means to be engaged by the cards being compressed by the adjustable wall to counteract the rod-projecting means and move the rod to a position where it will not engage a cabinet portion on movement of the drawer to housed relation, the finger having an extension, and cam means on the drawer, the extension and the cam means cooperating to make the projecting means ineffective when the adjustable wall is adjusted to a predetermined position with relation to the front wall and the drawer is substantially empty.

22. In combination, a cabinet, a drawer for storing material, the drawer being movable into and out of housed relation within the cabinet, means movable relatively to the drawer for engaging material stored in the drawer, means for effecting movement of the engaging means automatically from any position where the engaging means has not compressed the material to en-

gage said material and then to compress the material to a predetermined degree as the drawer is moved into housed position, and means for making the movement-effecting means ineffective when the engaging means has placed the stored material under a predetermined degree of compression.

23. A follower block for a drawer of a cabinet, the follower block consisting of a compressor plate for engaging material stored in the drawer to be compressed, a signalling device, means carried by the block for supporting the signalling device at limits of movement, one of the limits being when the device is positioned substantially entirely within bounds defined by the edges of the plate, the other limit being when the device is beyond said bounds, and means carried by the block for actuating the supporting means to position the device at the limit within said bounds when the plate engages and compresses the stored material.

24. A follower block for a drawer of a cabinet, the follower block consisting of a compressor plate for engaging material stored in the drawer to be compressed, a signalling device, means carried by the block for supporting the signalling device at limits of movement, one of the limits being when the device is positioned substantially entirely within bounds defined by the edges of the plate, the other limit being when the device is beyond said bounds, the supporting means normally retaining the device at the limit beyond said bounds, and means carried by the block for actuating the supporting means to position the device at the limit within said bounds when the plate engages and compresses the stored material.

MILTON EFFROS.
CHARLES E. MILLS.
